UNITED STATES PATENT OFFICE.

ROY EVERHART, OF MARSHALL, TEXAS, ASSIGNOR TO HIGHWAY ADVERTISING CO.,
OF MARSHALL, TEXAS.

DESIGN FOR AN ADVERTISING SIGN.

Application filed August 3, 1926. Serial No. 18,583. Term of patent 14 years.

To all whom it may concern:

Be it known that I, Roy EVERHART, a citizen of the United States, residing at Marshall, in the county of Harrison and State of Texas, have invented a new, original, and ornamental Design for an Advertising Sign, of which the following is a specification, reference being had to the accompanying drawings, forming part thereof.

Figure 1 is a front elevation of an advertising sign showing my new design.

Figure 2 is a edge view thereof.

I claim:

The ornamental design for an advertising sign, as shown.

ROY EVERHART.
